UNITED STATES PATENT OFFICE.

CLINTON O. HARRINGTON, OF EDGEWOOD BOROUGH, PENNSYLVANIA, ASSIGNOR TO
THE UNION SWITCH & SIGNAL COMPANY, OF SWISSVALE, PENNSYLVANIA, A COR-
PORATION OF PENNSYLVANIA.

SIGNAL.

1,127,199.

Specification of Letters Patent.

Patented Feb. 2, 1915.

Application filed May 20, 1914. Serial No. 839,712.

To all whom it may concern:

Be it known that I, CLINTON O. HARRINGTON, a citizen of the United States, residing at Edgewood Borough, in the county 5 of Allegheny and State of Pennsylvania, have invented certain new and useful Improvements in Signals, of which the following is a specification.

My invention relates to signals and particularly to signals of the type in which a 10 source of light is employed for giving indications both at night and in daylight.

Signals embodying my invention are particularly adapted for use in railway signaling, although they are not limited to this 15 particular adaptation. When a signal of the type mentioned is used on a railway curve, the beam of light projected by the signal should be visible over all points on 20 the curve in the rear of the signal. Hence, this beam is preferably elongated in a horizontal direction, but not in a vertical direction. Furthermore, it is desirable that the beam should appear to be about the same 25 intensity from all points on the curve, hence the beam preferably varies progressively in intensity from a maximum value adjacent one end to a minimum value adjacent the other, the more intense portion of the light 30 being directed toward the end of the curve farthest from the signal and the less intense portions being directed toward the sections of the curve nearer to the signal.

One feature of my invention is the provision of a signal which will project a beam 35 of this character.

I will describe several forms of signals embodying my invention and will then point out the novel features thereof in claims.

40 In the accompanying drawings, Figure 1 is a top view showing one form of signal embodying my invention. Fig. 2 is a view showing a lamp having a modified form of filament, which lamp may be substituted for the lamp L shown in Fig. 1. Figs. 3 and 4 are views showing lamps having still other forms of filament, either of which may be substituted for the lamp L shown in Fig. 1. Fig. 5 is a group of curves showing the 45 distribution of candle-power along the line X-Y of the signal shown in Fig. 1, and also along the same line when the lamps 50

shown in Figs. 2, 3 and 4 are substituted in this signal. Fig. 6 is a view showing a railway curve provided with a signal embodying my invention.

Similar reference characters refer to similar parts in each of the views.

Referring first to Fig. 1, the signal here shown comprises an incandescent electric 60 lamp L from which a beam of light is projected by a lens 2. Although I have here shown a lens, it is understood that any other suitable optical means may be employed for projecting a beam of light from 65 lamp L.

The incandescent lamp L comprises a filament B which is elongated in a horizontal direction perpendicular to the axis O-K of lens 2, one end of the filament being located substantially in this axis and the balance of the filament extending to one side of the axis. With this form and arrangement of lamp filament, the intensity of light at various points along line X-Y in front 75 of the signal varies substantially as indicated by curve b in Fig. 5, from which it will be seen that the greatest intensity of light is in the axis O-K, that the intensity decreases rapidly to the left of the axis, and 80 that the beam is elongated with gradually decreasing intensity to the right of the axis. Therefore, by so arranging the signal as to bring optical axis O-K of the lens substantially in line with the end of a railway curve 85 farthest from the signal, the portion of the beam of greatest intensity will be directed toward that point and the intensity of the light will vary progressively, as can be seen from curve b, from the maximum value adjacent the optical axis to a minimum value 90 adjacent one end, and will therefore appear to be of about the same intensity from all points of the curve.

Referring now to Fig. 2, the lamp L' here shown is the same as lamp L shown in Fig. 1, except that the portion of the filament B' which lies in the axis O-K is highly concentrated, that is, it consists of a large number of turns in a comparatively small 100 space, while the balance of the filament extends to one side of the optical axis in a manner similar to filament B in Fig. 1.

With the lamp filament B' arranged in

this manner, the variation of intensity of the beam along the line X—Y is as indicated by curve b' in Fig. 5. From the curve it is seen the point of greatest intensity is obtained from the concentrated portion of filament B' located in the optical axis O—K and that the intensity of the beam at this point is somewhat greater than that obtained from filament B. However, it is seen from the curve b' that the intensity of beam varies progressively from a maximum value adjacent the axis to a minimum value adjacent one end, and will therefore appear to be approximately the same intensity from all points of the curve.

In Figs. 3 and 4 I have shown lamps L^2 and L^3 having filaments B^2 and B^3 which vary progressively in concentration from a maximum value at one end to a minimum value at the other end, each lamp being so located that the optical axis O—K of the projecting means passes through the most highly concentrated end of the filament. These filaments are preferably helical in form, and in the case of filament B^2 the variation of concentration is obtained by progressively decreasing the diameter of the successive turns, while the variation in filament B^3 is obtained by progressively increasing the pitch of the successive turns. With filaments of this design used in place of filaments B and B' of Figs. 1 and 2, the distribution of candle-power along the line X—Y is substantially as indicated by curve b^2 in Fig. 5, which is approximately the ideal distribution of candle-power for illuminating a railway curve.

In Fig. 6 I have shown a railway curve F at one end of which is a signal S, which may be any one of the several forms shown herein. The signal is so located that the most intense portion of the light, that is, the portion along the axis, is directed toward section E which is farthest from the signal, and the portions of the light of progressively decreasing intensity are directed toward sections M, N and G of the curve progressively approaching the signal. Hence, as an observer passes along the curve F toward the signal, the light is constantly visible and constantly appears of substantially the same intensity. There is, therefore, no light wasted in unnecessarily intense illumination at any one part of the curve.

Although I have herein shown only a few forms of signals embodying my invention, it is understood that various changes and modifications may be made therein within the scope of the appended claims without departing from the spirit and scope of my invention.

Having thus described my invention, what I claim is:

1. A signal comprising an incandescent electric lamp, and means for projecting a

beam of light from said lamp, the lamp filament being elongated in a direction substantially perpendicular to the axis of said projecting means, and so located that one end of said filament is substantially in the said axis.

2. A signal comprising an incandescent electric lamp, means for projecting a beam of light from said lamp, the lamp filament being elongated in a direction substantially perpendicular to the axis of said projecting means, and so located that one end of said filament is substantially in the said axis, and the portion of the filament lying in and adjacent to the axis being more highly concentrated than the remainder of the filament.

3. A signal comprising an incandescent electric lamp and optical means for projecting a beam of light from said lamp, the filament of said lamp being elongated in a direction perpendicular to the axis of said projecting means and one end of the filament being located in said axis, and the concentration of said filament varying from a maximum value adjacent the end in the axis to a minimum value at the other end.

4. A signal comprising an incandescent electric lamp and optical means for projecting a beam of light from said lamp, the filament of said lamp being helical and elongated in a direction perpendicular to the axis of said projecting means and one end of the filament being located in said axis, the concentration of said filament varying from a maximum value adjacent the end in the axis to a minimum value at the other end, said variation of concentration being obtained by progressively decreasing the diameter of the successive turns.

5. A signal comprising an incandescent electric lamp and optical means for projecting a beam of light from said lamp, the filament of said lamp being helical and elongated in a direction perpendicular to the axis of said projecting means, and one end of the filament being located in said axis, and the concentration of said filament varying from a maximum value adjacent the end in the axis to a minimum value at the other end, said variation of concentration being obtained by progressively increasing the pitch of the successive turns.

6. A signal comprising a source of light, and means for projecting a beam of light from said source, said source being elongated in a direction substantially perpendicular to the axis of the projecting means, and one end of the source being located substantially in said axis.

7. A signal comprising a source of light, and a lens for projecting a beam from said source, said source being elongated in a direction substantially perpendicular to the axis of the lens, and one end of said source being located substantially in said axis.

8. A signal comprising a source of light, and means for projecting a beam from said source, said source being elongated in a direction at an angle to the axis of said projecting means, and said source being displaced so that its center lies outside of said axis.

In testimony whereof I affix my signature in presence of two witnesses.

CLINTON O. HARRINGTON.
